OLINDO O. CECCARINI, OF BEVERLY HILLS, CALIFORNIA, ASSIGNOR TO METRO-GOLDWYN-MAYER CORPORATION, OF CULVER CITY, CALIFORNIA, A CORPORATION OF NEW YORK

DAMPED LIGHT VALVE

Application filed January 7, 1931. Serial No. 507,194.

This invention relates to an apparatus for modulating light for the purpose of producing sound records.

A light modulating device of this general character is generally referred to as a light valve and will be thus identified hereinafter.

This invention particularly relates to a light valve capable of modulating light with greater accuracy so that the sound records obtained by the use of the improved light valve are substantially free of resonant frequencies and transient frequencies having their origin in the resonant frequency of the light valve itself.

The light valve of this invention is particularly adapted to be used in the recording of sounds for subsequent reproduction in proper timed relation with the reproduction of scenes such as motion pictures.

The equipment ordinarily employed in sound recording comprises a plurality of microphones or sound collecting means which are connected to a mixer controlling the gain of amplifiers for the recording machines.

The current from the microphones then passes through an amplifier, one or more equalizers and an attenuator and then into the recording machines. The recording machines (when photographic records of the sounds are being made) generally include a constant source of light and a light valve through which the signal currents from the amplifiers are passed.

A lens system is ordinarily employed, such lens system being adapted to focus the image of the slit made by the light valve on a continuously moving film.

The light valve of the prior art generally comprised a loop of metallic tape suspended in a plane at right angles to a magnetic field. The amplified voice currents passing through such tape when the electromagnet (of which the light valve assembly is a part) is energized from a battery or other source of direct current cause the two sections of the ribbon or loop to open or close in accordance with the current alternations, thereby increasing or decreasing the width of the aperture through which the light is being passed.

The volume of light thus modified pro-

duces a variable density record on the moving film, the record generally assuming the form of striations.

The metallic loop described hereinabove is under tension and the natural frequency of the valve, that is, the natural period of resonance of the metallic tape or loop is dependent upon the distance between the bridges supporting the loop and the mass and tension of the tape or ribbon.

For structural purposes or other considerations light valves of the character described hereinabove have a natural period of resonance above 8000 cycles. The power required to fully modulate a light valve at resonant frequency is only a very small fraction of the power required to fully modulate the light valve at any other frequency. Furthermore, transients are capable of exciting the valve at the resonant frequency very readily and therefore sound records produced with ordinary light valves are unsatisfactory because of the almost constant presence of vibrations or sounds other than the true sounds which it is desired to record.

Again, light valves of the character used heretofore not only vibrate in a plane transverse to the magnetic field but in addition the ribbons appear to oscillate and tip, very often hitting the pole pieces, thereby destroying the true naturalness of the recorded sounds.

An object of this invention is to disclose and provide a light valve which will not respond to transient impulses.

Another object is to disclose and provide a light modulating device which is of simple construction which has a relatively high natural resonance period and which will not respond to transient impulses.

A still further object is to disclose and provide a light modulating device in which the movable light modulating element vibrates in a predetermined plane and is not readily dislodged therefrom.

An object of this invention is to disclose and provide a light valve which employs but a single vibrating element, such light valve being provided with a damping means.

Another object is to disclose and provide a light valve provided with means for absorb-

ing transient vibrations while permitting oscillatory currents to energize and actuate the valve.

These and other objects, uses and advantages of the invention will become apparent to those skilled in the art from the following detailed description of one preferred form thereof.

In describing the invention, reference will be had to the appended drawing, in which:

Figure 1 is a plan view of the improved light valve assembly.

Figure 2 is an enlarged transverse section taken along the plane 2—2 indicated in Figure 1.

Figure 3 is an enlarged transverse section taken through one of the damping devices.

As shown in Figure 1, the light valve may comprise an armature plate 1, provided with pole pieces 2 and 3. The armature plate 1 may be provided with an aperture 4, and a bore of rectangular cross-section horizontally, and of conical cross-section vertically, indicated at 5, may be provided in the pole pieces 2 and 3. Bridges 6 and 7 may be carried by the armature plate 1. The metallic tape 8 may be connected to an anchor post 9 extending from a suitable bracket or holder 10 carried by the armature plate 1, the anchor post 9 being electrically connected to a terminal post 11 leading to the source of oscillating current from the amplifiers. The opposite end of the wire tape 8 may be connected to a swivel post 12 pivotally connected to armature plate 1 by a pin 13.

The lower member of the swivel post 12 may be provided with a semi-circular depression in its upper surface, a rod 14 being carried by the swivel post 12 and removably connected thereto as by means of a machine screw 15. The end of the wire tape 8 may be held between the swivel post 12 and the rod 14, said rod resting in the semi-circular concavity in the upper surface of the swivel post 12 and held therein by means of the machine screw 15, the tape 8 being thus grippingly held between the lower jaw of the swivel post 12 and the rod 14. A grounded electrical connection may be made between the swivel post 12 and a terminal post 23 carried by the plate 1 as by means of a coiled or flexible conductor wire 17.

The bridges 6 and 7 (made of non-conducting material) maintain the central portion of the tape 8 slightly above the upper surfaces of the pole pieces 2 and 3, preferably the central portion of the tape 8 lying about two-thousandth of an inch above the upper surfaces of the pole pieces. Furthermore, the ribbon or tape 8 is positioned in such manner as to lie in alignment with the longitudinal axis of the rectangular slit formed in the pole pieces 2 and 3 so that when at rest one longitudinal edge of the ribbon 8 lies substantially along the center line of the rectangular

slit in the pole piece. Such positioning of the ribbon 8 is facilitated by means of side guards 18 and 19 carried by each of the bridges 6 and 7, such side guards 18 and 19 contacting with the side edges of the ribbon 8 and maintaining it approximately in the required position with regard to the aperture in the pole pieces.

The ribbon 8 is maintained under tension by means of a spring 20 connected to one end of the pivoted anchor member 12, the other end of the spring 20 being adjustable by means of machine screw 21, such machine screw 21 passing through the side walls 22 of the light valve and through the bus member 23 by means of which grounded contact is made with the armature plate 1.

One of the pole pieces, such as for example, the pole piece 3, may have its upper surface slightly milled down so as to receive a partial shield 24, such partial shield being carried by means of a non-magnetic supporting member 25 to which the shield is attached as by means of screws 26. The member 25 may in turn be attached to the pole piece as by means of the screws 27.

The upper surface of the shield 24 is preferably either in the same plane as or one-thousandth of an inch above the upper surface of the pole piece 2. The shield 24 partially covers the rectangular slit in the pole pieces, thus permitting the ribbon 8 to modulate the light passing through the remaining opening.

Positioned between the bridge members 6 and 7 and the pole pieces 2 and 3 are damping devices 30 and 31. Such damping devices may consist merely of tubular or cylindrical members provided with depressions in their upper ends, such members being suitably attached to the armature plate 1.

As shown in greater detail in Figure 3, the damping device may be provided with a depression 32 in its upper end, diametrically opposed apertures 33 being made in the side walls. These apertures 33 are preferably of a width exceeding the width of the ribbon 8. If, for example, the ribbon 8 is six mills wide, the aperture 33 may be twice as wide. These damping devices 30 and 31 are then preferably filled with a suitable lubricant or non-volatile viscous medium such as petroleum jelly, grease, highly refined non-volatile oil, a soap compound or similar substance which does not evaporate, has a high surface tension, does not flow readily, and which, at the same time, exhibits plastic flow and is sufficiently plastic and elastic so as to absorb the vibrations of the ribbon 8 to a certain extent.

It has been found that ordinary grease, such as is employed for heavy bearings on automobiles, has the proper consistency for the purposes of this invention.

The apertures 33 formed in the upper end of the damping devices 30 and 31 are of suf-

ficient depth so that the ribbon 8 is completely surrounded by the lubricant in the chambers 32 of such damping devices.

It has been found that light valves constructed as above described and employing but a single ribbon or light modulating element are particularly effective in recording speech and music. Recordings produced by means of devices of this character are characterized by a brilliance of tone and distinctness, and for the fullness of tone above all.

Furthermore, it has been found that the ribbons 8 above the pole pieces do not sway along arcuate paths with the points of suspension on the bridge elements 6 and 7 as pivotal points, but instead, the ribbons merely vibrate in a flat plane. The tipping or angular position which the ribbons have formerly assumed when impulses of great amplitude pass through the ribbons, is completely obviated. There is no tendency for the ribbons to thus become jammed and contact with the pole pieces or become lodged in an angular position.

It is to be understood that it is not necessary to employ the shield 24 and the shield supporting element 25 unless it is desired to transform one of the valves of the prior art into a damped single element valve of the character embraced by this invention. The shield may be dispensed with wherever the rectangular slot or slit in the pole pieces does not exceed in width the width of the modulating ribbon and one edge of the slot is sufficiently straight and accurate. Furthermore, the invention is not to be limited to the precise form of bridges or ribbon anchoring devices. The form of the damping devices may also vary. It is very essential, however, that some form of damper be positioned within the vibrating section of the ribbon as, for example, between the bridge members and the pole pieces.

Numerous changes and modifications can be made in the arrangement of the elements and in their construction and form. All such changes and modifications as come within the scope of the appended claims are embraced thereby.

I claim:

1. An improved light valve adapted to be activated by an oscillating current comprising an armature member, an aperture in said armature member, means for supporting a metallic tape over said armature member and over said aperture therein, a metallic tape suspended over said aperture and damping means carried by said armature member between said supporting means and aperture, said damping means being adapted to hold a damping medium in contact with the metallic tape.

2. An improved light valve adapted to be activated by an oscillating current comprising in combination an armature member, an

aperture in said armature member, means for supporting a metallic tape over said armature member and over said aperture therein, a metallic tape suspended over said aperture and damping means carried by said armature member between said supporting means and aperture, said damping means comprising a chamber, opposed apertures in the walls of said chamber adapted to loosely receive the metallic tape and a damping medium carried in said chamber and surrounding said metallic tape.

3. An improved light valve adapted to be activated by an oscillating current comprising an armature member, pole pieces carried by said armature member, a slit in said armature member and pole pieces, bridge means for supporting a metallic tape over said pole pieces and over the slit therein, a metallic tape suspended over said aperture, means for maintaining said tape under tension, and damping means carried by said armature member between said supporting means and pole pieces, said damping means being adapted to hold a damping medium in contact with the metallic tape.

4. An improved light valve adapted to be activated by an oscillating current comprising in combination an armature plate, pole pieces carried by said armature plate, a slit in said pole pieces, bridge means carried by said armature plate for supporting a metallic tape over said pole pieces and slit therein, a metallic tape suspended over said pole pieces, a shield carried by one of said pole pieces and partially covering said slit therein, means for maintaining said tape under tension, and damping means carried by said armature plate between said bridge means and pole pieces, said damping means comprising a chamber, opposed apertures in the walls of said chamber adapted to loosely receive the metallic tape, and a damping medium carried in said chamber and surrounding said metallic tape.

Signed at Culver City, Calif., this 29th day of Dec., 1930.
